UNITED STATES PATENT OFFICE.

JAMES EDGAR, DECEASED, LATE OF BROOKLYN, NEW YORK, BY JOHN FREDERIC PIERSON AND JAMES R. PIERSON, EXECUTORS, OF NEW YORK, N. Y.

CUREYCOMB.

1,172,688.

Specification of Letters Patent. Patented Feb. 22, 1916.

Application filed April 29, 1910. Serial No. 558,499.

To all whom it may concern:

Be it known that JAMES EDGAR, deceased, late a citizen of the United States and a resident of Brooklyn, county of Kings, and 5 State of New York, has invented certain new and useful Improvements in Curry-combs, of which the following is a specification.

The object of this invention is the production of increased strength and durability of construction of curry combs with coincident reduction of the number of parts and the cost of manufacture and assemblage thereof.

The novel features of construction and arrangement will hereinafter more fully appear and the same form the subject of the appended claims.

Figure 1 represents in longitudinal section, on line I—I of Fig. 3, a curry comb embodying this invention showing the handle in elevation; Fig. 2 is a vertical section on line II—II of Fig. 1 in the direction of the arrows; Fig. 3 is a plan view of the same curry comb; Fig. 4 represents a view in perspective of the front combing bar provided with the improved integral knocking lugs of this invention.

The curry comb comprises a one-piece back-plate 1 formed with an integral shank 2 extending into a handle 3 which may be of wood. The combing or scurfing bars 4 are formed of flat blanks of sheet metal bent into inverted U shape with right angled corners and secured to the back plate, each by 35 two rivets 5, a strengthening shank or brace 6 extends under the back plate centrally thereof and is inserted in the handle 3 preferably for half the length thereof, so that the back-plate, comb-bars and handle form 40 one complete rigid structure. The back plate is formed with two raised or embossed stiffening ribs 7 diverging forwardly from a point adjacent the end of the shank 2 and merging at their forward ends into a raised 45 or offset end portion 8. Such offset end portion constitutes a lateral stiffening rib and forms a seat for the front combing bar as will be hereafter more fully described. The raised or embossed ribs 9 extending longitudinally of the back plate adjacent the edges thereof are also and preferably provided thereon, to aid in stiffening the structure. The combing bars 4 of inverted U shape each form two blades 4" which may 55 be provided with the usual scurfing edges or

teeth 10, or some or all of the blades may be formed with smooth edges, without teeth, if desired. The flat backs 4' of one or more of the U-shape comb bars are extended in projecting relation beyond the ends of the vertical combing or scurfing blades 4" thereof, as more plainly shown in Figs. 2 and 4, and such extended ends are stamped or pressed into semi-spherical or rounded shape as shown at 11, or they are otherwise crimped or stiffened, so that they are adapted to withstand shocks and blows of considerable force without yielding or bending. It is preferred to form only one of the comb bars of the curry comb with such extended integral ends and to locate such comb-bar in the seat on the back plate formed by the offset portion 8 thereof, in which position it is secured by two rivets, one at each end of the bar and with the crimped end portions 11 projecting laterally from the margin of the back-plate 1 and constituting knocking blocks upon which the curry comb may be struck against the floor or other solid object to dislodge accumulations of dirt and scale 80 therein.

By means of the construction above described the strain and shock due to such use of the knocking lugs is most advantageously received since the lugs are integral with a 85 combing bar and lie closely in the plane of the back plate by reason of the offset 8 thereof and by reason of the fact that such offset forms a rib that is connected to other ribs in such a manner that the strain is distributed throughout the extent of the back plate and thence to the handle.

It will readily be seen that a curry comb embodying this invention is of great 95 strength, and comprises a minimum number of parts there being required only two rivets for securing each combing bar in position and no extra rivets for the knocking lugs, the strain thereon being effectually guarded against through the design and construction of the back plate and the novel positioning of the combing bar having the knocking lugs integral therewith.

While a particular form of curry comb embodying this invention is above shown and described it will readily be understood by those skilled in the art that changes and modifications may be made in the design, construction, combination and location of parts without departing from the spirit of 110

the invention as set forth in the claims here-to appended.

Claims:

1. In a curry comb, the combination with a sheet metal back plate, of a U-shaped sheet metal combing bar secured beneath the forward part of said plate and having the ends of its top portion extended to form knocking lugs, said knocking lugs being of cupped 10 formation.
2. In a curry comb the combination of a sheet metal back plate having an upwardly pressed reinforcing channel extending across its forward portion, a sheet metal combing 15 bar secured beneath the forward part of said plate at said channel and having its ends extended beyond the plate and forming cup-shaped knocking lugs.
3. In a curry comb the combination of a sheet metal back plate having a transverse 20 rib extending across its forward portion and

diverging ribs extending from the base of the shank portion obliquely forward and outward and connecting with the end portions of such transverse rib and forming 25 therewith a triangular reinforcement of said metal back plate, with a combing bar secured on said transverse rib at the under side of the back plate and having its ends extended beyond the sides of the plate to 30 constitute knocking lugs, said knocking lugs being of cupped formation.

In testimony whereof, we have signed our names, in the presence of two subscribing witnesses.

JOHN FREDERIC PIERSON,
JAMES R. PIERSON,
Executors of estate of James Edgar, deceased.
